ELECTRIC SWITCH

James W. Woolf, Franklin, Pa., assignor to Joy
Manufacturing Company, Pittsburgh, Pa., a
corporation of Pennsylvania

Application August 30, 1949, Serial No. 113,154

11 Claims. (Cl. 200—98)

1

This invention relates to an electric switch, especially to a latch type reversing switch.

In mine haulage practice, it is common to use trolley shuttle cars in a great many applications. Where such shuttle cars have to operate on a grade or slope, it is desirable to provide them with dynamic braking. When two cars have to pass on a hill or slope, the car going downhill must get off the trolley in order that the car going uphill may continue under power. With controlling circuits heretofore in use in shuttle cars, it has not been possible to provide dynamic braking during the time that the shuttle car is off the trolley, because with the power removed the reversing switch contacts would drop out and interrupt the armature circuit of the drive motors.

It is, accordingly, an object of this invention to provide a reversing switch suitable for mine shuttle car applications which will not open its contacts upon failure of the power source for any reason. This and other objects are accomplished in a reversing switch having latch means so arranged that the contacts are latched against opening and are opened when the latch is released upon operation of the switch to reverse the contacts.

In the drawings:

Fig. 1 is a top plan view of a reversing switch made according to this invention.

Fig. 2 is a side elevation of the switch, with the mounting panel in section.

Fig. 3 is a view in section on line 3—3 of Fig. 2.

Fig. 4 is a view in section on line 4—4 of Fig. 2, but shown without the movable contacts.

Fig. 5 is a view in section on line 5—5 of Fig. 4; and

Fig. 6 is a partial view in side elevation, similar to Fig. 2, but showing the contacts reversed from the position shown in Fig. 2.

A mounting panel of any suitable non-conducting material is shown at 2, and serves as a non-conducting member on which a non-magnetic support 4 is mounted by any suitable fastener means 6. The support 4 is preferably an inverted U and may be provided with a stiffening member 8 to brace the legs of the U.

A fixed electrical contact 10, which may be referred to as a first contact, is mounted on the non-conducting member 2 by any suitable means such as screws 12. In a preferred form of the invention, the fixed or first contact 10 takes the shape of a U, one leg of which is secured to the panel 2 as aforesaid, and provides a terminal to which a conductor 14 may be secured in good

2

electrical contact relation. The actual fixed or first contact referred to thus constitutes the other leg of the U and is spaced a substantial distance from the panel 2. Preferably, there are 5 two such contacts 10, as is best seen in Figs. 1 and 3.

Two magnetic base members 16 are provided, one for each of a pair of electromagnets 18 and 20. In a preferred form of the invention, magnets 18 and 20 and magnetic base members 16 are secured to the support 4 by fastening means shown at 22. The fastening means 22 may consist of threaded members passing through openings in the base members 16 and threadedly 15 engaging cores 24 and 26 of magnets 18 and 20, respectively. The details of the engagement of cores 24 and 26 by screws 22 will be well understood by those skilled in the art and need not be shown here.

20 An armature is provided for each magnet as shown at 28 and 30. These armatures are pivotally mounted on the non-magnetic support 4 by means of bolts 32 passing through and clamping bifurcated members 34 of the armatures and passing freely through openings 36 in the non-magnetic support 4. In a preferred form of the invention, the non-magnetic support 4 is made of brass and the bolts 32 are made of iron or steel, whereby a good bearing is provided 25 for the pivoting of the armatures 28 and 30. A light spring 38 is provided to bias the armatures 28 and 30 away from their respective magnet cores 24 and 26. Springs 38 are preferably L-shaped, one leg of the L being placed against 30 the non-magnetic support 4 and the other leg being clamped between a latch member and the armature.

Each armature is thus provided with a latch member, armature 28 being provided with a latch member 40, and armature 30 having a latch member 42. Suitable fastening means, such as screws 44, secure each latch member to its armature.

45 A second armature is provided for each magnet, armature 46 being shown as associated with magnet 18 and armature 48 being shown as associated with magnet 20. The two armatures 46 and 48 are mounted for pivotal movement on support 4 by means of bolts 50, in much the same 50 manner as armatures 28 and 30 are mounted by means of bolts 32. Movable contacts 52 and 54 are mounted on armatures 46 and 48, respectively. Inasmuch as contact 10 was referred to above as a first contact, contacts 52 and 54 may be referred to as second and third contacts.

Although the details of mounting the second and third contacts 52 and 54 do not per se form a part of this invention, it may be pointed out briefly that the contacts 52 and 54 are carried on contact holders 56, which are pivotally mounted at 58 on brackets 60. Brackets 60 are mounted on transverse insulating blocks 64 and 66, which in turn are mounted on the armatures 46 and 48 respectively. Springs 68 are provided between one end of each contact holder 56 and its respective bracket 60 to provide a yielding pressure or bias of the contacts 52 and 54 against the fixed contact 10, or against a stop 69 when the movable contact is not engaging the fixed contact.

Flexible conductor 70 engages contact 52, and a similar flexible conductor 72 engages contact 54. There are preferably two movable contacts 52 and two movable contacts 54, one on each side of the switch, for engagement with the two fixed contacts 10. Correspondingly, there are two flexible conductors 70 and two flexible conductors 72, as may best be seen in Figs. 1, 3 and 4. The two flexible conductors 70 engage terminals 74 and 76, and the two flexible conductors 72 engage terminals 78 and 80. The terminals are mounted on an insulating panel member 81. In order to provide the conventional reversing-switch circuit, terminals 74 and 80 are cross-connected by a conductor strap 82, and terminals 76 and 78 are cross-connected by a conductor strap 84. The conductor strap 84 is insulated in any suitable manner from the strap 82, as for example by means of a non-conducting sheath 86.

Latch members 40 and 42 were referred to above. A third latch member 87, consisting of a block 88 and side members 89, is supported by both of the armatures 46 and 48 by means of bolts 90. Thus, the latch member 87 serves as a link connecting the two armatures 46 and 48. As is best seen in Fig. 5, block 88 of latch member 87 is notched out to provide recesses 92 and 94 for the engagement respectively of latch members 40 and 42. Thus, the latch members 40, 42 and 87 form latch means for holding the contacts in a selected engagement, as will be more fully brought out in the description of the operation.

Operation

Let it be assumed that a shuttle car with a reversing switch, made according to the invention, is proceeding downhill with its switch parts occupying the relative positions shown in Fig. 2 and Fig. 5. With the switch parts as thus shown, latch member 42 engages recess 94, thus cooperating with the latch member 87 to hold it in its extreme leftward position and to keep the movable contact 54 in engagement with fixed contact 10. If then the shuttle car has to get off the trolley for any reason, taking the electromagnet 18 off the power source, contacts 10 and 54 will, nevertheless, remain in engagement, because of the latch means just described. The armature circuits of the drive motors thus remain closed and the vehicle continues to operate with dynamic braking.

Let it now be assumed that the vehicle is again on the trolley and that it is desired to reverse the drive motors. The operator makes the necessary manipulation of manually or pedally operated controls, whereupon electromagnet 20 is energized. The close proximity of the armature 30 to the lower end of magnet core 26 makes it possible for magnet 20 to attract armature 30, pulling the latch member 42 out of the recess 94. With ar-

5 ture 30 in its attracted position, the flux path for armature 48 is through the upper end of armature 48, magnetic base member 16, magnet core 26 and part of armature 30. The air gap then exists between the lower end of armature 48 and the left end of armature 30. Armature 48 is thereupon attracted toward armature 30, disengaging the contacts 10 and 54. Inasmuch as latch member 87 serves as a link connecting the armatures 46 and 48, armature 46 is also moved toward the right as seen in Fig. 2, causing engagement of contacts 10 and 52. With the parts in this position, latch member 40 is free to drop into the recess 92, whereupon the parts take the position shown in Fig. 6 and the contacts 52 and 10 are latched in engagement.

10 The reverse of the operation, i. e., going from the position shown in Fig. 6 to the position shown in Fig. 2, will be readily understood by those skilled in the art from the above description and need not be detailed here.

15 Among the advantages of a switch made according to this invention is that of maintaining the contacts in engagement, even after the system is disconnected from the power source (or in case of a power failure for any reason whatever), making it possible in the application of the invention referred to herein to keep the shuttle car or other vehicle operating with dynamic braking. Other advantages will be apparent to those skilled in the art.

20 While there is in this application specifically described one form which the invention may assume in practice, it will be understood that this form of the same is shown for purposes of illustration, and that the invention may be modified and embodied in various other forms without departing from its spirit or the scope of the appended claims.

I claim:

25 1. In an electric switch, a first contact, a second contact and a third contact, the contacts being mounted to provide relative movement of two of them with respect to the other whereby said first and second contacts are engaged to provide a desired electric circuit through the switch and alternatively said first and third contacts are engaged to provide another desired electric circuit through the switch, latch means for holding the contacts in a selected engagement, the latch means including three latch members, two electromagnets, a first armature for each of said two magnets, one of the three latch members being supported by one first armature and another of the three latch members being supported by the other first armature, and a second armature for each of said two magnets, the third latch member and the second and third contacts being supported by both of said second armatures.

30 2. A switch according to claim 1, in which the flux path for each second armature includes at least a portion of its associated first armature.

35 3. In combination, a non-conducting member, an electrical contact mounted on the member, a non-magnetic support mounted on the member, a pair of magnetic base members, a pair of electromagnets, means to secure each electromagnet with one of said base members to the support, an armature for each magnet, a second armature for each magnet, an electrical contact mounted on each said second armature and movable thereby into engagement with the first-named electrical contact, a latch member supported by both of the second armatures, and another latch

member on each first-named armature and co-operable with the first-named latch member.

4. The combination of claim 3, in which the flux path for the second armature includes at least a portion of the first armature.

5. The combination of claim 4, in which the first-named latch member is connected to said second armatures and serves as a link to connect them.

6. The combination of claim 3, in which the first-named latch member is connected to said second armatures and serves as a link to connect them.

7. The combination of claim 3, in which the armatures are pivotally mounted on the non-magnetic support.

8. In combination, a non-conducting member, an electrical contact mounted on the member, a non-magnetic support mounted on the member, a pair of electromagnets, means to secure each electromagnet to the support, an armature for each magnet, a second armature for each magnet, an electrical contact mounted on each said second armature and movable thereby into engagement with the first-named electrical contact, a latch member supported by both of the second armatures, and another latch member on each first-named armature and co-operable with the first-named latch member.

9. The combination of claim 8, in which the

flux path for the second armature includes at least a portion of the first armature.

10. The combination of claim 9, in which the first-named latch member is connected to said second armatures and serves as a link to connect them.

11. The combination of claim 8, in which the first-named latch member is connected to said second armatures and serves as a link to connect them.

JAMES W. WOOLF.
